CONTROL MEANS FOR SLIDING BOLT DOOR CATCHES

Richard Murray Turner, Kew, Australia

Application May 21, 1936, Serial No. 80,941
In Australia July 5, 1935

3 Claims. (Cl. 292—165)

This invention relates to means which are adapted to be actuated by push-pull handles to retract catches of sliding bolt type, which may be combined with lock mechanism and which is usable on doors and other hinged structures.

One object of this invention is to provide simple, effective, durable, and inexpensive means to retract sliding bolts of the type indicated.

Another object of this invention is to provide bolt retracting means which may be combined with lock mechanism of known construction without materially altering the construction of such mechanism.

Control means for catches of sliding bolt type, according to this invention, is characterized by a longitudinally slideable actuating bar or rod which is so constructed that when it is moved from a normal position it retracts a slideable bolt which is arranged at right angles to it or it actuates means to retract such a bolt.

In one embodiment of this invention the actuating bar or rod is so formed that when moved longitudinally it rotates a rollback which in turn retracts a slideable catch or bolt. Preferably the said bar or rod is a flat strip which is twisted helically and which slidably engages a slot of complementary shape in the boss of the rollback. In a modified construction the bar may be of other suitable cross section or be screw threaded and the tumbler is provided with a complementary hole.

In a further modified arrangement part of the bar or rod is inclined or wedge-shaped to co-act with part of a sliding bolt in such manner that when the said bar or rod is moved longitudinally from its normal position, the bolt is retracted.

But in order that this invention may be more readily understood, practical embodiments thereof will now be described with reference to the accompanying drawings in which:

Fig. 1 is an end elevation showing part of a door having a lock of mortise type fitted therein, including twisted bar mechanism to actuate a rollback to retract the lock bolt.

Fig. 2 is a side view of the parts in Fig. 1.

Figs. 3 and 4 are detail views including a spring bolt and retracting means therefor of the type illustrated in Figs. 1 and 2. In Fig. 3 the bolt is in normal projected position while in Fig. 4 it is retracted.

Figs. 5 and 6 are detail views showing a rollback and an actuating bar or rod at right angles to the positions shown in Figs. 3 and 4 respectively.

Fig. 7 is a detail perspective view of rollback elements formed of sheet metal.

Fig. 8 is a perspective view of a rollback comprising elements as shown in Fig. 7, in assembled position.

Fig. 9 is an end view of a lock having modified actuating means.

Fig. 10 is a side view at right angles to Fig. 9, with parts broken away to disclose the sliding bolt and parts associated therewith.

Fig. 11 is a sectional plan of the parts in Figs. 9 and 10.

In the arrangement illustrated in Figs. 1 to 6, 15 is a sliding bolt which is actuated toward its normal projecting position by a spring 16 in known manner and which is retractable by a partially rotatable rollback 17, also in known manner.

An actuating rod 19 which is helically twisted at 19^a engages a suitably shaped slot 18 in the boss 17^a of the rollback 17. The respective ends of rod 19 are pivotally connected to lever handles 20^a, 20^b by pins 22 each of which is located in a convenient hole 22^a. There may be a plurality of holes 22^a to facilitate fitting to doors of different thickness. The upper end of each handle 20^a, 20^b is supported on a pivot pin 20^c which engages a lug 21^a on a plate 21 which is fixed to a face of the door D.

The lower part of each handle 20^a, 20^b is offset at 20^d to facilitate access to a keyhole 20^e that is associated with lock mechanism (not shown) which may be of any suitable type. Handle 20^a normally projects outwardly obliquely and is adapted to be actuated by inward pressure so that when it is pushed in the direction of arrow 20^f it first moves the bar 19 longitudinally to rotate the rollback 17 and so retract the bolt 15, and continuation of the pressure opens the door D. The upper part of handle 20^b is normally parallel with the door D (or nearly so) and its lower part projects sufficiently to be gripped by a user. This handle is actuated by a pull in the direction of arrow 20^g to move the bar 19 and so actuate the rollback 17 to retract the bolt 15 and then open the door as before described.

Each handle may be provided with a rubber or other suitable buffer such as rubber block 23 to minimize noise and to absorb any jar.

It will be apparent that the form of bar 19 may be modified, for example the said bar may be replaced by a twisted rod of square or other suitable cross section or a round bar having a screw thread on its exterior, may be used. In any such case the hole in the rollback is suitably

modified so that the rollback operatively engages the said bar in such manner that when the bar is moved longitudinally from normal position the rollback is partially rotated.

5 The rollback 17 may be cast or otherwise suitably formed in one piece or it may comprise a plurality of members 17^b, 17^c and 17^d formed of sheet metal as shown in Fig. 7 and fixed together in any suitable manner to form a rollback as 10 shown in Fig. 8.

In the modified arrangement shown in Figs. 9 to 11 the actuating bar or rod is a longitudinally slideable bar 19^a on which is a wedge-shaped projection 19^y. The said bar extends through a 15 hole 15^a in a bolt 15^b and its wedge 19^y operatively engages a wall 15^c thereof. Bolt 15^b is 20 slidably arranged in a casing 15^d in known manner and it is normally actuated to operative projecting position by a spring 16^a. The ends of 25 bar 19^a are pivotally connected to lever handles as 20^f, 20^g by which the bar is actuated in manner previously described. Although no lock mechanism has been illustrated in Figs. 9 to 11 it will be apparent that the described arrangement may 25 be combined with such mechanism while retaining features according to this invention.

I claim:

1. Control means for catches of the sliding bolt type comprising a reciprocable bar the medial part of which is helically twisted through an 30 angle that does not exceed 180 degrees, a roll-

back mounted on the twisted part of said bar, two members arranged to be fixed to opposite faces of a door, two handles, means to pivotally connect one end of each handle to one of said members, and means to pivotally connect the 5 ends of said bar to respective handles so that the free end of each handle may be actuated as a lever to move the said bar longitudinally to partially rotate the rollback.

2. A control means for catches of the sliding 10 bolt type, as claimed in claim 1, in which said reciprocable bar consists of a flat strip of oblong cross section which is twisted through 180 degrees, in combination with a rollback having an aperture the shape of which is complementary to 15 the cross sectional shape of said strip.

3. Control means for catches of the sliding bolt type comprising a reciprocable bar the medial part of which is helically twisted, a rollback mounted on the twisted part of said bar, 20 two plates each thereof having apertures through which an end of the said bar is arranged to project, a lug on each said plate, two lever type handles, means to pivotally connect an end of each handle to one of said lugs, means to connect 25 the ends of said bar to respective handles whereby either handle may be actuated as a lever to move the said bar longitudinally, the free end of each handle being offset to facilitate access to a key hole. 30

RICHARD MURRAY TURNER.
